UNITED STATES PATENT OFFICE.

ROBERT C. MATTHES, OF WYOMING, NEW JERSEY, ASSIGNOR TO WESTERN ELECTRIC COMPANY, INCORPORATED, OF NEW YORK, N. Y., A CORPORATION OF NEW YORK.

ELECTRIC-CURRENT TRANSMISSION.

Application filed October 9, 1923. Serial No. 637,438.

To all whom it may concern:

Be it known that I, ROBERT C. MATTHES, a citizen of the United States, residing at Wyoming, in the county of Essex and State 5 of New Jersey, have invented certain new and useful Improvements in Electric-Current Transmission, of which the following is a full, clear, concise, and exact description. The invention relates to the transmission 10 of electric currents, and aims to provide improvements in the two-way transmission of such currents, for instance in the two-way repeating of telephonic currents.

In the specific forms of the invention illustrated in the accompanying drawings, a repeater connected between two sections of a two wire circuit and comprising the usual unilaterally transmitting paths for repeating in opposite directions between the sections and the usual impedance balance networks for the sections, has means energized in accordance with the currents flowing in the networks in response to transmission in each direction in the system, for reducing 20 the transmission in the opposite direction, to thereby reduce "echo effects" in the circuit. The nature and effects of echo currents have been explained by A. B. Clark in his article on Telephone Transmission over Long 25 Cables, Journal of the American Institute of Electrical Engineers, January, 1923, page 1, and reference may be had to that article for a better understanding of the phenomena of echo effects.

In the preferred form of the invention the transmission reducing means energized in accordance with the currents in the networks comprises a switch for rendering the repeating path in one direction inefficient to 30 transmit, the switch having a winding energized from across the balancing network for the line section which extends from the repeater in the opposite direction, and also an opposing winding energized from across the path that is to have its transmitting efficiency reduced by the operation of the switch. This opposing winding tends to 35 prevent false operation of the switch when transmission approaches the repeater over 40 the last mentioned line section. A switch is also provided for rendering the repeating path in said opposite direction inefficient to transmit, and this switch is energized like the other, that is, by an operating winding 45 connected across the balancing network for

the line section extending in said one direction from the repeater, and by an opposing winding connected across this path. A delay circuit, that is, a circuit which has the property of appreciably delaying the propagation of currents therethrough, is inserted in each path in advance of the switch that reduces the transmitting efficiency of the path, so that the operation of that switch may be effected before an objectionable 50 amount of transmission from the other path can pass that switch. The time required to reduce the transmitting efficiency of the desired repeating path is small because the necessary switching is accomplished by the 55 mere opening of a contact; and therefore the amount of apparatus required in the delay circuit is small.

By a two-wire line or circuit is meant, a 60 circuit of the type used where transmission in both directions between two points, geographically remote from each other, are to be carried over the same pair of wires for the greater portion of the distance between the points, as distinguished from a four-wire 65 circuit which is a circuit of the type used where the transmission in one direction for the greater portion of the distance between two points, geographically remote from each other, is carried over a different pair of 70 wires from the currents in the other direction.

Fig. 1 of the drawings is a circuit diagram of one form of the invention; and Fig. 2 is a similar showing of the preferred 75 form.

In Fig. 1 two-wire lines 5 and 6 forming part of a two-wire transmission system, for example, a telephone system, are interconnected by a two-wire repeater comprising 80 repeater amplifiers 7 and 8 for transmitting in the directions indicated by the arrows and the usual three-winding transformers 9 and 10 and balancing networks 11 and 12. The amplifiers 7 and 8 may be of any suitable 85 type, but are preferably of the electron discharge type.

A relay 13 has four windings fed by amplifier-rectifiers 21, 22, 23 and 24 respectively, the amplifier-rectifiers 21 and 22 being 90 fed from the hybrid coil or three-winding transformer 9 and the amplifier-rectifiers 23 and 24 being fed from the hybrid coil 10, as indicated, so that for transmission east, that is, for transmission from line 5 to line 6, 95 100 105 110

amplifier-rectifiers 21 and 24 receive current but, due to the property of conjugacy possessed by the hybrid coil connection, amplifier-rectifiers 22 and 23 receive little or no current, and, for transmission west, 23 and 22 receive current but 24 and 21 receive little or no current. Each of the amplifier-rectifiers is shown merely as a block, and preferably comprises an electron discharge amplifying tube, or such tubes in tandem, feeding a three electrode electron discharge amplifying and rectifying tube, as described hereinafter in connection with Fig. 2. Forms of amplifier rectifiers particularly suitable for operating voice relays are disclosed in R. V. L. Hartley application Serial No. 602,273, filed November 20, 1922, transmitting electric energy, and E. D. Johnson Patent 1,526,550, February 17, 1925, two-way transmission with repeaters, and my application Serial No. 667,437, of even date herewith, all assigned to the assignee of this application, and the amplifier-rectifiers 21 to 24 may advantageously be of such forms.

The armature of relay 13 is normally biased to a neutral position between two contacts 25 and 26, and the windings of the relay tend to operate the armature about its pivot in the directions indicated by the arrows on the respective windings. This operation can be obtained, for example, by polarizing the relay core to cause a flux in the direction of the arrows pointing to the right in the drawing. When talk is passing from west to east the relative magnitudes of the operating impulses are such that the relay tongue (normally not in contact) is moved to contact 25, and repeater 8 then has its input short circuited, through a transformer 27. When talk is passing from east to west the relay tongue is moved to contact 26, and repeater 7 then has its input short circuited, through a transformer 28. Thus the relay is controlled by two circuits each affecting the relay selectively in accordance with the direction of transmission through a hybrid coil. That is, the relay is controlled by two directional circuits of the hybrid coil type, a type claimed in my application Serial No. 653,624, filed July 25, 1923.

Blocks N_{22} and N_{24} represent networks for balancing the impedances of amplifier rectifiers 22 and 24, respectively, as regards the hybrid coil connection, so as not to disturb the impedance balance of the circuit for the normal two-way repeater function of this coil.

In the operation of the system, when talk is passed from west to east, relay 13 closes its contact 26 as noted above, and consequently any echo currents or other currents which may tend to flow from line 6 into repeater amplifier 8 or amplifier-rectifier 23 due for instance to impedance unbalance at

repeater stations in line 6 or reflection from terminal apparatus or the like, are short circuited through transformer 27. Also, any current tending to enter the input of 8 or 23 from the output of 7, because of impedance unbalance between the line and network at hybrid coil 10, are short circuited, through 27.

The operation of the system in transmitting from east to west is similar to the operation just described, and will be evident without further description.

The lines 5 and 6 may, of course, embody repeaters other than that shown connecting them, and any desired ones of such other repeaters may be provided with echo suppressing means of the character described above. However, although where the number of repeaters in tandem is large the number of possible echo paths is large, the introduction of one or two breaks or short circuits in the system may be made to cut down the number of such paths materially and, furthermore, to cut out those involving the greatest time lag.

The relay 13, to be effective, must be quicker operating than in the case of a voice relay for a four wire echo suppresser, such for instance, as that disclosed in John Mills Patent No. 1,434,790, November 7, 1922, "two-way transmission with repeaters", but should have an equivalent time of release, depending upon the type of circuit and the distance to the terminal station, so that at least the primary echo current from that station will be prevented from passing the relay 13. If the release time is too long the relay will unduly interfere with the ability of the listener to break in on the talker.

The functioning of the circuit described above is such that when no speech is traversing the circuit both repeaters are operative substantially their full gain permitted by the degree of balance obtained between the connected lines and their balancing networks, but when speech is applied the inactive repeater path is rendered inoperative to transmit. This enables the repeaters to be set much nearer their singing points.

If desired, where good balance can be secured between the bridge impedance and the series impedance of the hybrid coils, the amplifier-rectifiers 21 and 23 and the switch windings fed by them may be omitted from the system of Fig. 1.

In Fig. 2 the elements 5' to 12' correspond to the elements 5 to 12, respectively, of Fig. 1. Delay circuits 30 and 31 are preferably connected in the repeater paths comprising the amplifiers 7' and 8', respectively. These delay circuits are preferably filters connected in the input circuits of the repeater amplifiers, and, as repeater filters, function in the manner disclosed in G. A. Campbell Patent No. 1,227,114, May 22, 1917, "electrical

receiving, translating or repeating circuit." The filters may be, for example, low pass filters such as those shown at 1^g in Fig. 11 of the patent, or shown in Fig. 7 of the patent, comprising recurrent sections each having a series arm containing lumped inductance and a shunt arm containing lumped capacity. The filters are here employed not merely for the purpose of frequency separation, but especially as delay circuits to delay the propagation of signaling currents therethrough for reasons which will be made apparent hereinafter. The delay circuits need not necessarily have filtering properties but may be circuits or means of any type suitable for producing the desired delay in current propagation.

An amplifier rectifier 41 such as is referred to above has its input connected preferably across the input of delay circuit 30, and feeds upper winding of a relay 50; and the lower winding of the relay is fed from a similar amplifier rectifier 42 preferably connected across the balancing network 11'. Similarly an amplifier-rectifier 43 connected across the input of delay circuit 31 feeds the lower winding of a relay 51; and the upper winding of relay 51 is fed from an amplifier-rectifier 44 connected across the balancing network 12'. The relays 50 and 51 are normally biased to the positions shown in the drawing, for example, by a spring overcoming the attraction due to the normal polarization of the relay. The windings of these relays tend to operate the relay armatures in the directions indicated by the arrows on the respective windings. Thus, each relay is controlled by a hybrid coil type of directional circuit.

The transmission path between the hybrid coil 9' and the input of repeater element 7' extends through the armature and upper contact of relay 50 and through the armature of a normally closed relay 60, in series and when relay 50 moves its armature to its lower contact, a local circuit through the winding of relay 60 is closed, to cause relay 60 to open its contact. When relay 50 thereafter again closes its upper contact, the transmission path between hybrid coil 9' and the input of repeater element 7' still remains open until relay 60 closes. Relay 50 is preferably designed to open its upper contact quickly, and relay 60 is preferably designed to be slow in releasing its armature, for reasons which will be made apparent hereinafter.

The relay 51 with the cooperation of a relay 61 corresponding to relay 60, controls the repeater path west in the manner in which the relay 50 with the cooperation of relay 60 have just been described as controlling the repeater path east. Although not essential that this control of these paths be at the input sides of the repeater ele-

ments in the respective paths, it is preferable that the opening of these paths be accomplished at this point, rather than, for example, between the outputs of the repeater elements 7' and 8' and the series windings of the hybrid coils 10' and 9', respectively so that the opening of the switches will not disturb the energy distribution in the impedances connected to the hybrid coils. Resistance 75 is a resistance such as is commonly connected across the primary winding of the input transformer for an electron tube repeater, for instance as at 12 in K. S. Johnson Patent 1,432,863, Oct. 24, 1922, and preferably matches, or is of the order of the delay circuit impedance which faces it. Similarly, resistance 76 is preferably substantially equal to the delay circuit impedance which faces it.

The output impedance of the repeater amplifier 8' may vary considerably, depending upon the particular electron tube being used in the amplifier, and to avoid unbalance between the bridge and series impedances of hybrid coil 9' due to this variation in artificial resistance line 70 may, if desired, be inserted in the output of repeater amplifier 8' the impedance of this artificial line being adjusted to match the bridge and series impedances of the hybrid coil for the particular tube employed in repeater 8'. The amplification or gain of the repeater amplifier 8' may be correspondingly increased, to make up for the transmission loss in the artificial line 70.

Similarly, an artificial resistance line 71 may be inserted in the output of the repeater amplifier 7', to insure good balance between the bridge and series impedances of hybrid coil 10'.

Also, a section of artificial resistance line 72 may, if desired, be inserted in front of the delay circuit 30, to improve the balance between the bridge and series impedance of the hybrid coil 9', and the amplification of the repeater amplifier 7' and that of the amplifier-rectifier 41 may be correspondingly increased to compensate for the transmission loss in the artificial line 72. Similarly, an artificial resistance line 73 may be inserted in front of the delay circuit 31, to improve the balance between the bridge and series impedances of hybrid coil 10', and the amplification of the repeater amplifier 8' and that of the amplifier-rectifier 43 may be correspondingly increased to make up for the transmission loss in this artificial line.

The provision of these artificial lines 70 to 73 is especially beneficial in case it is desired to omit amplifier-rectifiers 41 and 43 and the relay windings controlled thereby from the system.

The operation of the system will now be described for transmission from west to east, and the operation for transmission

from east to west, which is similar, will then be evident without further description.

A part of energy coming to the repeater from line 5' is transmitted through the 5 hybrid coil 9' and the armatures of relays 50 and 60, and is amplified by repeater element 7' in the usual fashion. Another part is transmitted through the coil 9' and acts through amplifier-rectifier 41 to hold the relay 50 on its upper contact. Part of the 10 output of 7' is taken off by amplifier-rectifier 44 and applied to relay 51 to move the armature of relay 51 from its lower to its upper contact, thereby opening the input of 15 repeater 8'. The transmission, approaching the repeater from the west, that is over line 5', is at a higher energy level going to amplifier rectifier 44 than direct into amplifier-rectifier 42 because of the gain of the 20 eastwardly directed repeating path as well because of the high transmission loss in transmitting from line 5' to network 11' due to the impedance balance between the bridge and series of impedances of hybrid 25 coil 9'.

As soon as relay 51 opens, all circulating unbalance currents are stopped and echoes from line 6' are cut off. Upon cessation of talk, the closing of the input to repeater 20 amplifier 8' should be delayed by a time equal to the time of the longest echo, and this is accomplished by the relay 61.

The seriousness of the effect of the circulating currents which are set up before the 35 switching operation takes place depends upon the length of time of the switching and also upon the amount of increased equivalent which may be desired from the repeater when provided with the echo suppressing 40 means, that is, also upon how close it is desired to make the gain of the repeater approach its singing point for the condition 45 of the circuit in which both the repeating path east and the repeating path west are in condition to transmit. The circuit of Fig. 2 gives a very low switching time since the switching operation is performed by merely opening a contact and the time required for opening a contact is far less than 50 the time required for the travel of an armature to a satisfactory make or closing contact. Furthermore, the amount of circulating current built up may be reduced to any desired degree by increasing the time lag 55 introduced by the delay filters, for instance by increasing the number of sections in the filters; for if the transmission in one of the repeater paths is delayed in the filter in that path until that path has been opened by the 60 echo suppressing switch, no circulating current can flow.

When the time lag in the filters equals the switching time even the initial unbalance currents, which tend to cause false operation 65 of the switch controlling the active repeater

path and which result from the fact that the transient impedance of a network such as 12' differs from that of a perfectly regular line such as 6' for instance would be in the ideal case, have no opportunity to circulate. 70 Under those circumstances the gain of the repeater amplifying elements may be pushed near the singing point without injuring the quality of transmitted speech. On the other hand, if it is only necessary to eliminate 75 the longer echoes in a circuit without giving it a lower transmission equivalent or loss, the time of switching need not be so short or the lag in the delay circuits so great. In such a circuit the gain of the repeater is 80 usually so far below the singing point that the local circulating currents do not seriously affect the quality. The actual requirements, as regards switching time and time of propagation through the delay circuit, 85 may lie all the way between these two extremes. The use of a quick operating switching means tends to reduce the number of sections of delay circuit required for satisfactory operation. 90

To reduce the effect of line noise upon the operation of the repeater of Fig. 1 or the repeater of Fig. 2, the grid potentials of the rectifier tubes employed in the amplifier-rectifiers should preferably be set so that a 95 definite minimum alternating current input to the rectifier or rectifiers which are to operate the relay to render one repeating path inoperative is required before the relay gets sufficient rectified input to be operated; for 100 if, instead, it be attempted to protect the relay against line noises below a given minimum by biasing the relay, as for instance by a biasing current in an auxiliary winding (not shown) or the relay, then, noise energy 105 being amplified in substantially the same ratio as speech energy, substantial gain in the speed of operation of the relay is not readily obtained by increasing the driving or operating energy, since the biasing current 110 must be correspondingly increased. Where the desired margin against noise is secured by choking off the noise energy before it reaches the relay circuit, the speed of operation of the relay can be made high by applying 115 a high value of driving or operating energy thereto. In certain cases the adjustment may be such that the relays operate only for eliminating the most severe echoes due to the louder parts of the speech. This setting may be advisable, for instance, where line noise is a serious factor, or where, due to the long length of a line or the connection of a number of echo-suppressing repeaters in tandem in the line, the operation of the 120 echo-suppressing means tends to render it difficult for a listener to break in on a speaker. 125

The application of a delay circuit to a voice controlled repeater to delay transmis- 130

sion until the voice operated switching means has had time to operate is claimed in H. D. Arnold application Serial No. 338,759, November 17, 1919, "two-way repeater circuits," assigned to the assignee of this application.

The general principles herein disclosed may be embodied in many organizations widely different from those specifically illustrated and described without departing from the spirit of the invention defined in the appended claims.

Although the invention has been set forth with special reference to its application to the repeating of voice frequency currents, it is of course also applicable to the transmission and repeating of currents of other frequencies, whether higher or lower, as for instance currents of the frequencies commonly used for radio and carrier currents.

What is claimed is:

1. A transmission system comprising two circuits, two oppositely directed unilaterally transmitting repeating paths, means connecting said paths to said circuits and connecting said paths in conjugate relation to each other, and means responsive to potentials produced on said first mentioned means by amplified currents from said repeating paths for controlling transmission in said system.
2. A transmission system comprising two circuit, impedance balancing networks for said circuits, two oppositely directed unilaterally transmitting repeating paths interconnecting said circuits and said networks, and means energized in accordance with the transmission flowing into one of said balancing networks from one of said paths for controlling transmission in said system.
3. A transmission system comprising two circuits, two oppositely directed unilaterally transmitting repeating paths, means connecting said paths to said circuits and connecting said paths in conjugate relation to each other, and means responsive solely to potentials produced on said first mentioned means by amplified currents from said repeating paths for controlling transmission in said system.
4. A transmission system comprising two circuits, two oppositely directed unilaterally transmitting repeating paths, means connecting said paths to said circuits and connecting said paths in conjugate relation to each other, and means responsive to potentials produced on said first mentioned means by amplified currents from said repeating paths, and also to transmission in said paths, for controlling transmission in said system.
5. A transmission system comprising two circuits, two oppositely directed unilaterally transmitting repeating paths, means connecting said paths to said circuits and connecting said paths in conjugate relation to each other, and means responsive to poten-

tials produced on said first mentioned means by amplified currents from said repeating paths for controlling transmission in said system, said paths comprising means for delaying transmission therethrough substantially until said transmission controlling means has operated.

6. The method of operating a two-way, two-channel repeating system comprising the usual three winding transformers and balancing networks for the line sections between which the repeating system is connected, which comprises controlling transmission in the channel in one direction in response to transmission flowing from the other channel into the balancing network for the line extending in the opposite direction from the repeating system.

7. A two-wire transmission system comprising two lines and a 22-type repeater therefor, said repeater comprising impedance balancing networks for said lines, respectively, two oppositely directed unilaterally transmitting paths for repeating in opposite directions between said lines, means comprising a movable switch contact for controlling transmission through the path in one direction immediately upon the opening of said contact, means responsive to transmission flowing from the path in the other direction into the balancing network for the line extending in said other direction from the repeater for opening said contact without delay due to other mechanical motion, transmission delaying means connected in said path in said one direction in advance of the point therein at which said transmission controlling means effects control of transmission, said transmission delaying means delaying transmission therethrough substantially until said contact has opened.

8. A transmission system comprising two circuits, two oppositely directed unilaterally transmitting repeating paths, means connecting said paths to one of said circuits and connecting said paths in conjugate relation to each other, delay means in one of said paths for appreciably delaying the propagation of transmission therethrough, and an artificial resistance line connected between said first mentioned means and said delay means.

9. A transmission system comprising two circuits, two oppositely directed unilaterally transmitting repeating paths, means comprising an impedance balancing network for one of said circuits for connecting said paths to said circuit and for connecting said paths in conjugate relation to each other, a relay responsive to transmission flowing into said balancing network from one of said paths for controlling transmission in said system, delay means in the other of said paths for delaying the propagation of trans-

- mission through said delay means for a time substantially equal to the time required for said relay to operate, and an artificial resistance line connected between said first mentioned means and said delay means.
10. In combination, two circuits, means comprising two balanced impedances for connecting said circuits in conjugate relation, a relay energized in accordance with the current flowing from one of said circuits into one of said impedances, and an artificial resistance line connected between said means and said one circuit.
11. Two pairs of circuits, means for connecting one pair of said circuits in conjugate relation and for connecting the other
- pair of said circuits in conjugate relation when the impedances looking from said means toward said circuits are of proper values, one circuit of one of said pairs comprising an amplifier feeding into said means and also comprising an impedance connected between said means and the output of said amplifier, said impedance having a value such that the impedance looking from said means toward said amplifier output is of the proper value to render the other pair of said circuits conjugate.
- In witness whereof, I hereunto subscribe my name this 2nd day of October, A. D. 1923.

ROBERT C. MATHES.
